COMBINED TABLE AND MIRROR UNIT

Thomas McCartan, Chicago, Ill., assignor to Bee and Gee Manufacturing Co., Inc., Chicago, Ill., a corporation of Illinois

Application April 22, 1958, Serial No. 50,571

Term of patent 14 years

(Cl. D33—6)

Fig. 1 is a view in perspective of a combined table and mirror unit showing my new design;

Fig. 2 is an elevational view;

Fig. 3 is a top plan view; and

Fig. 4 is a bottom plan view thereof.

I claim:

The ornamental design for a combined table and mirror unit, substantially as shown.
